[57] CLAIM

The ornamental design for a fishing pole holder, as shown and described.

DESCRIPTION

FIG. 1 is a front perspective view of a fishing pole holder, showing our new design;

FIG. 2 is a rear perspective view thereof, the broken line showing of environment being for illustrative purposes only and forming no part of the claimed design;

FIG. 3 is a bottom perspective view thereof;

FIG. 4 is a top plan view thereof; and,

FIG. 5 is a right side elevational view, the left side being a mirror image thereof.

FIG. 1

FIG. 2

FIG. 3

FIG. 4

FIG. 5
